UNITED STATES PATENT OFFICE.

GUSTAV EGLOFF AND HARRY P. BENNER, OF INDEPENDENCE, KANSAS, ASSIGNEES TO
UNIVERSAL OIL PRODUCTS COMPANY, OF CHICAGO, ILLINOIS, A CORPORATION OF
SOUTH DAKOTA.

PLUG COCK.

Application filed April 1, 1921. Serial No. 457,795.

To all whom it may concern:

Be it known that we, GUSTAV EGLOFF and HARRY P. BENNER, both citizens of the United States, residing in the town of Independence, county of Montgomery, and State of Kansas, have invented certain new and useful Improvements in Plug Cocks, of which the following is a specification.

This invention relates to improvements in plug cocks and refers more particularly to a construction particularly adapted in connection with petroleum distillation where the valve plug is subjected to high temperature and high oil pressure. A great deal of trouble has been experienced where cracking processes are used in petroleum refining where high pressure is used to find any type of valve or cock which will work satisfactorily at high temperature and pressure. Some of the difficulties are due to the unequal expansion and contraction stress between the bottom of the valve and disk or in the case of a plug between its body and the plug.

The object of the present invention is to provide an efficient water cooled plug adapted for the use referred to which can be readily assembled or removed and which is economical and simple in construction and yet effective in operation.

In the drawing, the single figure is a view partly in vertical section and partly in side elevation of our improved construction.

Referring to the drawing, *a* designates the valve plug adapted to be mounted in the seats *a'* and *a''*. The plug is held firmly in place by means of the coiled expansion springs *b* and the anti-friction members *b'*, and *b''*, carried by the spring and plug respectively. The arrangement is such that

the plug can be turned independently of the spring. The spring is held in position by means of the screw-threaded cap *c* having a boss *c'* to receive a wrench. The valve plug is provided with a stem *e* and a head *d* to receive a wrench whereby the plug may be turned. In order to make an oil tight fitting, we provide a packing *f* held in place by the packing gland *g* and screw bolts *h*. The valve is water cooled by means of the water cooling jacket *j*, water being admitted through the pipe *k* and drawn off through the outlet *l*. In order to be able to adjust the spring by adjusting the cap *c*, we provide a screw-threaded plug *m* having a wrench head *m'*. Screw-threaded holes *n* are tapped in the face of the valve to receive stud bolts to be used in connection with the flanges on the line to which the cock is to be applied.

The operation of the device is apparent from the foregoing description and need not, therefore, be described in detail.

We claim as our invention:

In a plug cock, the combination with a casing having a water jacket therein with water inlets and outlets in communication therewith, a valve cock mounted within the inner wall of said casing and having a turning portion extending through the outer wall thereof, said inner wall having an extension projecting therefrom in the water jacket, a cap adjustably mounted in said extension, a yieldable support for said valve seated on said cap and engaging the valve, and a removable plug in the exterior wall of the casing to permit adjustment of said cap.

GUSTAV EGLOFF.
HARRY P. BENNER.
